UNITED STATES PATENT OFFICE

124,311

DESIGN FOR A STUFFED DOLL OR SIMILAR ARTICLE

Arthur A. Gerling, New York, N. Y., assignor to Knickerbocker Toy Co., Inc., New York, N. Y., a corporation of New York

Application August 2, 1940, Serial No. 94,144

Term of patent 7 years

To all whom it may concern:

Be it known that I, Arthur A. Gerling, a citizen of the United States, residing at New York city, in the county of New York and State of New York, have invented a new, original, and ornamental Design for a Stuffed Doll or Similar Article, of which the following is a specification, reference being had to the accompanying drawing, forming part thereof.

In the drawing
Fig. 1 is a perspective view of a stuffed doll showing my new design; and

Fig. 2 is a rear view thereof.

I claim:

The ornamental design for a stuffed doll or similar article, as shown.

ARTHUR A. GERLING.
